Design No. 3,854, dated February 22, 1870.

DESIGN FOR ORNAMENTING GLASSWARE.

The Schedule referred to in these Letters Patent and making part of the same

---

I, THOMAS B. ATTERBURY, of Pittsburgh, county of Allegheny, State of Pennsylvania, have invented a new and original Design for Glassware, of which the following is a specification.

The nature of my design is fully represented in the accompanying drawing, to which reference is made.

Figure 1 is a goblet, which fully shows the full pattern, being a drapery or curtain which is formed by dots or beads on the outside edge of the curtain, and the inside being composed of frosting, the same being hung with suitable tassels.

a represents a dotted band to form a portion of the border.

b is a diamond-shaped curtain, being formed with a beaded edge, and tassels attached to the ends of said curtain, which, together with the dotted band a, form the border of the pattern.

d is a larger curtain with a scallop edge, which is attached to the points of the diamond-point curtain b.

The tassels are hung from each of the scallops, as is shown, letter e.

c is a triangle-shape portion, made plain in order to more fully show the diamond-shaped curtain b.

Having fully described my invention, I do pray that Letters Patent of the United States may be granted for the term of three and a half years.

Claim.

I claim the design for ornamenting glassware, a curtain or drapery design, as shown and described.

T. B. ATTERBURY.
